Patented Aug. 3, 1920.

UNITED STATES PATENT OFFICE.

PEARL M. BIBB, OF MINDEN, WEST VIRGINIA.

RAIL-BENDER.

1,348,535.

Specification of Letters Patent. Patented Aug. 3, 1920.

Application filed April 18, 1917. Serial No. 162,927.

To all whom it may concern:

Be it known that I, PEARL M. BIBB, a citizen of the United States, residing at Minden, in the county of Fayette and State of West Virginia, have invented certain new and useful Improvements in Rail-Benders; and I do hereby declare the following to be a full, clear, and exact description of the invention, such as will enable others skilled 10 in the art to which it appertains to make and use the same.

This invention has for its object to provide an improved rail bender which shall be of simple construction and convenient 15 in operation.

With this and other objects in view, the invention consists in the novel construction, combination and arrangement of parts as will be hereinafter specifically described, 20 claimed and illustrated in the accompanying drawing, in which:

Figure 1 represents a perspective view of the rail bender, and

Fig. 2 represents a transverse sectional 25 view therethrough.

Referring to the drawing in detail, wherein similar reference numerals indicate corresponding parts throughout the several views, the numeral 5 indicates generally a substantially U-shaped frame including the web portion 6 and the parallel legs 7, having the recessed terminals 8 for receiving the head or base of the rail to be bent.

The web portion 6 is provided with a circular enlargement or lug 9, having spiral faces 10 thereon providing a substantially annular series of ratchet teeth, which are engaged with a wedge collar 11, provided with spiral faces 12 adapted to co-act with 35 the spiral faces 10 of the enlargement 9. The collar 11 is formed with an axial projection 13 of polygonal form, which is received in a correspondingly shaped opening 14 formed in the enlarged terminal 15 of a 40 turning handle 16.

The web portion 6 of the frame and the wedge collar 11 are formed with registering openings 17, receiving a slidable draw rod 18, having one end hooked, as indicated at 45 19, and provided adjacent its opposite end with a series of uniformly spaced apertures 20 adapted to receive a pin 21 for limiting the movement of the draw rod, in one direction, with relation to the frame of the 50 bender.

In operation the rail to be bent is seated in the recesses 8 in the terminals of the frame legs 7, and subsequent to removing the pin 21 from the draw rod 18, the hooked terminals 19 thereof are engaged with the 55 rail. The pin is subsequently inserted in the aperture 20 nearest the handle 15 and as the wedge collar 11 is turned by means of the handle 16 the inclined faces of the wedge collar working against those of the 60 enlargement 9 effect a longitudinal movement of the draw rod 18, thus drawing the latter inwardly toward the web 6 and bending that portion of the rail disposed between the frame legs 7. The bending operation may be continued until the rail is 65 bent into the desired shape, and it will be understood that at each operation the pin 21 is advanced one aperture 20.

What I claim is:

A rail bender including a substantially U-shaped frame having parallel legs and a relatively thick web, the ends of the legs having one of their side faces provided with aligned cutout portions forming shoulders, 70 an enlargement formed on the outer face of the central portion of the web provided with spiral faces, a draw rod slidably mounted in the web portion and enlargement, a wedge collar rotatably engaged with the outer face of the enlargement and slidably mounted on the draw rod, a reduced polygonal extension carried by the wedge collar, a handle non-rotatably engaged with the polygonal extension, said draw rod having the lower end thereof bent to provide 75 a hook to co-operate with the shoulders of the legs of the frame, and an adjustable pin carried by the draw rod for engaging the wedge collar and handle, whereby relative 80 movement between the handle, draw rod and wedge is eliminated when the device is in operation; as and for the purpose specified, and whereby the device may be quickly applied to the member to be bent from the 85 side thereof.

In testimony whereof I affix my signature in presence of two witnesses.

PEARL M. BIBB.
